by Rev Allen Atty.

UNITED STATES PATENT OFFICE

WILLIAM H. BAKER, OF MONTREAL, QUEBEC, CANADA

STOPPING MECHANISM FOR LOOMS

Application filed July 19, 1929. Serial No. 379,536.

This invention relates to improvements in stopping mechanism for looms, warping machines and other devices dealing with a series of separate threads moving side by side, in which the stopping mechanism becomes operative upon the breaking or excessive slackening of any of said threads. The primary objects of the invention is to enable the use, in connection with power knock mechanisms including a vibrating member adapted for operative engagement with a knock-off element, of stop mechanisms, embodying notched feeler bars sliding in notched guide bars and associated with drop wires supported by the threads normally out of operative engagement with the feeler bars and guide bars. A further object is to provide a novel manner of imparting operating force to stop mechanisms as aforesaid.

The invention comprises essentially the provision of a stop mechanism embodying notched longitudinally movable feeler bars associated with means operable by arrest of movement of any of the bars to so position a normally moving member that it will actuate a normally stationary member operatively connected to the knock off mechanism of the loom or other machine.

In the accompanying drawings which illustrate one embodiment of the invention but to which embodiment and the details thereof the invention is not confined as modifications of the illustrated embodiment and substitution of other embodiments are possible;

Fig. 1 is a fragmentary end elevation of a loom having knock off actuating mechanism independent of the lay, illustrating the manner of attaching warp stop mechanism thereto.

Fig. 2 is an end elevation of the warp stop mechanism as shown in Figure 1 but on a larger scale.

Fig. 3 is a fragmentary front elevation of the warp stop mechanism.

Fig. 4 is a fragmentary rear elevation of the warp stop motion.

Fig. 5 is a cross-sectional view of the vibrator wings at about the line 5—5 of Figure 2.

Referring more particularly to the drawings, 11 designates portions of a loom frame and 12 the usual main shaft. A shaft 13 is provided adjacent the main shaft and is operatively connected thereto by gears 14 adapted to rotate the shaft 13 at half the angular speed of the shaft 12. The shaft 13 carries a cam 15 adapted to oscillate an arm 16 pivoted to the frame at 17, one end of the arm being held in engagement with the cam by a spring 18 (or equivalent device) connected to a lug 19 on the arm. The end of the arm opposite to that engaging the cam carries pivotally mounted thereon a member 20 terminating in a catch 21 which, when the member 20 is in its normal position, is moved by the oscillation of the arm 16 back and forth over a lug 22 operatively connected to a knock-off rod 23 arranged in any suitable way to effect stopping of the loom.

Associated with the loom mechanism just described is a warp stop motion designated as a whole by the numeral 24, the said stop motion being mounted on the loom in the usual or any suitable manner, illustration of the actual mounting being however omitted as the same forms no part of the present invention. The type of warp stop motion herein contemplated embodies notched feeler bars sliding in notched guides and associated with drop wires each supported by a warp thread and designed to drop, upon breaking or excessive slackening of a warp thread, into the notches of the related feeler bar and guide, so as to arrest the motion of the feeler bar. As exemplary of this type of warp stop motion, there is illustrated an improved mechanism which is fully described in my prior application Serial Number 344,235, filed March 5th, 1929, to which application reference may be had, but it will be understood that the present invention is not confined to the particular warp stop motion illustrated and hereinafter described but extends to the use of all warp stop motions of the type formerly described in combination with loom stopping mechanisms of the type already described.

The warp stop motion comprises a framework 25 extending from end to end of a loom

as usual (although only one end of said framework is illustrated) and having at each end a cross bar 26 notched in its upper edge for reception of any suitable number of guide bars 27, which extend from end to end of the framework in the well known manner, as shown for instance in Patent No. 1,026,941, dated May 21, 1912. The lower edge of each guide bar may be notched, at one end at least, to receive the cross bar where it (the guide bar) rests in the cross bar notch, so that the cross bar and guide bar will be mutually embracing and the guide bar will be held against lateral and longitudinal movement. The guide bar is notched in its upper edge as indicated at 28. A feeler bar 29 is slidably mounted in the groove of each guide bar and is provided on its upper edge with notches 30 adapted to move to and fro across the notches of the guide bar as the feeler bar is longitudinally reciprocated in the guide bar. A guide bar retainer 31 is hinged to each end of the frame and is formed to normally overlie the ends of the guide bars and hold them against rising out of the cross bar notches. It will be understood that any other sort of guide bar supporting and retaining mechanism may be substituted.

The feeler bars may be reciprocated in any suitable way, for example, by means of flexible fingers 32 rigidly connected to a vibrator 33 and passing through studs 34 rigidly connected to the feeler bars and sliding in slots 35 in the guide bars. The vibrator is in turn mounted on a shaft 36 supported in the framework 25 and is connected releasably otherwise with an operating arm 37.

The operating arm 37 is connected by a rod 38 with a crank 39 fixed to the shaft 13. The rod 38 preferably passes through the end of the arm 37 and is adjustably secured by nuts 40 screwed on the rod above and below the arm. The preferred manner of connecting the rod with the crank is by means of an end piece 41 pivoted to the crank and adjustable along the rod and securable at any point by means of a set screw 42 or equivalent.

The effective position of the catch member 20 is determined by the condition of the feeler bars, that is, by whether the bars are free from unhampered reciprocation or whether the reciprocation of any one or more of them has been arrested by the falling of a drop wire.

In the particular warp stop motion illustrated, the positioning of the catch member 20 to actuate the knock off mechanism and to maintain the catch member in inoperative position comprises the following instrumentalities. A pair of wings 43 are hingedly mounted on the shaft 36 and embrace between them the feeler bar driving studs (see Figure 5). At the rear of the loom, the wings are provided with lugs 44 which converge toward one another (see Figure 4) and

are embraced between divergent walls 45 of a V-shaped notch provided on the upper end of a controller 46. The controller is a bar 75 slideable in an extension 47 of the vibrator, being supported in the vibrator extension toward its lower end in a guide lug 48 and toward its upper end between antifriction rollers 49. The lower end of the controller terminates in the axial line of the shaft 36 and bears against one arm 50 of a bell crank lever 51 pivoted in an extension 52 of the framework 25. A spring 53 is arranged in compression between the frame extension 52 and the other arm 54 of the bell crank lever and operates through the lever to press the controller against the wing lugs 44, so that by reason of the inclined or converging lugs 80 engaging in the V-shaped notch of the controller, the wings are yieldingly pressed against opposite sides of the feeler bar operating studs. The lever arm 54 carries an adjustably mounted extension 55 which terminates in a hook 56 located approximately vertically above the catch member. A rod 57 having at its upper end a hook 58 loosely hooked through the hook 56 depends toward the catch member and is provided with an adjustably mounted end piece 59 pivotally connected to the catch member. The spring 53 in holding up the lever arm 54 also holds 85 up the extension 55 and rod 57 to such extent that the catch member is held in such position during its reciprocation by the oscillating arm 16 that it does not engage the lug 22. It will be understood that other 90 mechanisms may be provided intermediate the feeler bars and the catch member 20 for the same purpose as the mechanism described and that substitution of any such other mechanism is contemplated in the scope of the 95 present invention.

The operation of the device briefly described is as follows:—Rotation of the half time shaft 13 causes oscillation of the arm 16 to reciprocate the catch member 20 over the stationary knock-off lug 22 and at the same time causes oscillation of the vibrator 33 to reciprocate the feeler bars. The spring 100 pressed controller 46, which is mounted upon and therefore oscillates with the vibrator, holds the wings in yieldingly clasping relation to the feeler bar operating studs, the wings oscillating with the vibrator. The engagement of the controller with the stationary lever 51 being in the axial line of the 105 shaft 36, which is the axis of oscillation, the spring pressure is transmitted substantially without friction and without causing any alteration in the relation of the controller and the wings.

If a warp thread should break or slacken sufficiently, the drop wire thereon falls upon the feeler bar threaded through it and eventually is caught in the notches of the feeler bar and its guide bar, thus arresting move- 110 115 120 125 130

ment of the feeler bar in the well known manner. Since the vibrator continues to oscillate, the movement of one or other of the wings, yieldingly connected to the vibrator for oscillation therewith and engaging the driving stud of the arrested feeler bar, will also be arrested. This stoppage of wing movement causes the controller notch to thrust laterally against the wing lug and, by reason of the inclination of the engaging surfaces of the lug and notch, the controller is forced downwardly and rocks the bell crank lever 51 against the pressure of the spring 53. This movement of the lever is communicated through its extension 55 and the rod 57 to the catch member 20, permitting the catch member to fall into position where its catch 21 will engage the lug 22 and transmit motion from the positively oscillated arm 16 to the knock-off actuating rod 23, so that the driving power is disconnected from the loom and the loom is stopped. When the defect causing the stoppage has been remedied, the spring 53 operating through the controller restores the affected wing to normal relation with the vibrator and, in process of this restoration, acts through the parts 55 and 57 to raise the catch member clear of the lug 22 so that the loom may be restarted.

Having thus described my invention, what I claim is:—

1. In a loom or the like including a normally stationary knock-off element, a normally reciprocating element for engagement with said knock-off element to stop the loom, a shaft, and operative connection between said shaft and the reciprocating element, the combination of a warp stop motion including longitudinally reciprocating feeler bars, operative connection between said shaft and said bars for reciprocation thereof, and operative connection between said bars and said reciprocating element normally holding the reciprocating element out of engagement with the knock-off element and operative upon arrest of movement of any feeler bar to permit engagement of the reciprocating element and knock-off element.

2. In a loom or the like including a normally stationary knock-off element, a normally reciprocating element for engagement with said knock-off element to stop the loom, a shaft, and operative connection between said shaft and the reciprocating element, the combination of a warp stop motion including stationary notched guide bars, longitudinally reciprocating notched feeler bars sliding on the guide bars and each adapted to be arrested in motion by engagement of a drop wire in a notch thereof and in a notch of the supporting guide bar, operative connection between said shaft and said bars for reciprocation thereof, and operative connection between said bars and said reciprocating element normally holding the reciprocating element out

of engagement with the knock-off element and operative upon arrest of movement of any feeler bar to permit engagement of the reciprocating element and knock-off element.

3. In a loom or the like, knock-off mechanism including a normally stationary knock-off lug and a reciprocating member for engagement with said lug, in combination with a warp stop motion including longitudinally reciprocating feeler bars, means operatively connected between said feeler bars and reciprocating member normally holding the reciprocating member out of lug engaging position and operative upon arrest of movement of any feeler bar to position the reciprocating member for engagement with said lug, a rotating element in the loom and separate operative connections between said element and the reciprocating member and between said element and the feeler bars.

4. The combination with elements of a loom or the like including a shaft, a cam thereon, an oscillating arm operated by said cam, a catch member pivotally connected to said arm for reciprocation thereby, a knock-off rod and a lug thereon for engagement by said catch member, of grooved guide bars notched in their upper edges, notched feeler bars slidable in the guide bar grooves, a vibrator connected with said feeler bars to reciprocate the same, a crank on said shaft, operative connection between the crank and vibrator and means operatively connected between said feeler bars and said catch member normally holding the catch member out of engagement with the knock-off lug, said means being operative upon arrest of movement of any feeler bar to release the catch for engagement with the knock-off lug.

5. The combination with elements of a loom or the like including a normally stationary knock-off element, a shaft, a cam thereon, an oscillating arm operated by the cam, a reciprocating element carried by the arm for engagement with said knock-off element to stop the loom, of notched guide bars, notched feeler bars longitudinally reciprocating on the guide bars and each adapted to be arrested in motion by engagement of a drop wire in a notch thereof and in a notch of the supporting guide bar, a vibrator connected with said feeler bars to reciprocate the same, a crank on said shaft, operative connection between the crank and vibrator, and means operatively connected between said feeler bars and said reciprocating member normally holding the reciprocating member out of engagement with the knock-off element, said means being operative upon arrest of movement of any feeler bar to release the reciprocating member for engagement with the knock-off element.

6. The combination with elements of a loom or the like including a normally stationary knock-off element, a shaft, a cam there-

on, an oscillating arm operated by the cam, a reciprocating element carried by the arm for engagement with said knock-off element to stop the loom, of notched guide bars, notched feeler bars longitudinally reciprocating on the guide bars and each adapted to be arrested in motion by engagement of a drop wire in a notch thereof and in a notch of the supporting guide bar, a vibrator connected with said feeler bars to reciprocate the same, a crank on said shaft, operative connection between the crank and vibrator, and means operatively connected between said feeler bars and said reciprocating member normally holding the reciprocating member out of engagement with the knock-off element, said means being operative conjointly by arrest of movement of any feeler bar and by continued operation of the vibrator to release the reciprocating member for engagement with the knock-off element.

7. In a loom or the like including a normally stationary knock-off element, a normally reciprocating element for engagement with said knock-off element to stop the loom, a shaft, and operative connection between said shaft and the reciprocating element, the combination of a warp stop motion including longitudinally reciprocating feeler bars, operative connection between said shaft and said bars for reciprocation thereof including a vibrator connected with the bars, means normally holding the reciprocating element out of engagement with the knock-off element, said means being adapted to be operated conjointly by arrest of movement of any feeler bar and by continued movement of the vibrator to release said reciprocating member for engagement with the knock-off element, said means including an arm hooked at its free end and a rod connected with the reciprocating element and hooked through the hooked end of the arm.

8. In a loom or the like including a normally stationary knock-off element, a normally reciprocating element for engagement with said knock-off element to stop the loom, a shaft, and operative connection between said shaft and the reciprocating element, spring actuated means normally holding said reciprocating element out of position for engagement with the knock-off element, and means operable upon arrest of movement of any feeler bar to move said spring actuated means to release the reciprocating element for engagement with the knock-off element.

9. In a loom or the like including a normally stationary knock-off element, a normally reciprocating element above the knock-off element adapted for engagement with said knock-off element to stop the loom, a shaft, and operative connection between said shaft and the reciprocating element, the combination of a warp stop motion including longitudinally reciprocating feeler bars, opera-

tive connection between said shaft and said bars for reciprocation thereof, and operative connection between said bars and said reciprocating element normally holding the reciprocating element elevated out of engagement with the knock-off element and operative upon arrest of movement of any feeler bar to permit downward movement of the reciprocating element into engagement with the knock-off element.

10. The combination with elements of a loom or the like including a shaft, a cam thereon, an oscillating arm operated by said cam, a catch member pivotally connected to said arm for reciprocation thereby, a knock-off rod and a lug thereon beneath said catch member adapted for engagement by said catch member, of grooved guide bars notched in their upper edges, notched feeler bars slideable in the guide bar grooves, a vibrator connected with said feeler bars to reciprocate the same, a crank on said shaft, operative connection between the crank and vibrator and means operatively connected between said feeler bars and said catch member normally holding the catch member elevated out of engagement with the knock-off lug, said means being operative upon arrest of movement of any feeler bar to release the catch for descent into engagement with the knock-off lug.

11. The combination with elements of a loom or the like including a normally stationary knock-off element, a shaft, a cam thereon, an oscillating arm operated by the cam, a reciprocating element carried by the arm above the knock-off element adapted for engagement with said knock-off element to stop the loom, of notched guide bars, notched feeler bars longitudinally reciprocating on the guide bars and each adapted to be arrested in motion by engagement of a drop wire in a notch thereof and in a notch of the supporting guide bar, a vibrator connected with said feeler bars to reciprocate the same, a crank on said shaft, operative connection between the crank and vibrator, and means operatively connected between said feeler bars and said reciprocating member normally holding the reciprocating member elevated out of engagement with the knock-off element, said means being operative conjointly by arrest of movement of any feeler bar and by continued operation of the vibrator to release the reciprocating member for descent into engagement with the knock-off element.

12. In a loom or the like including a normally stationary knock-off element, a normally reciprocating element for engagement with said knock-off element to stop the loom, a shaft, and operative connection between said shaft and the reciprocating element, the combination of a warp stop motion including stationary notched guide bars, longitudinally reciprocating notched feeler bars sliding on

the guide bars and each adapted to be arrested in motion by engagement of a drop wire in a notch thereof and in a notch of the guide bar, a vibrator including individual flexible driving connections for the feeler bars, means normally operating to hold said reciprocating member out of engagement with said knock-off element, and means actuated by the combined movement of the vibrator and 10 arrest of movement of any of said feeler bars to move said reciprocating member holding means to release the reciprocating member for movement into engagement with the knock-off element.

15 13. A structure according to claim 12, in which the means actuated by combined movement of the vibrator and arrest of movement of a feeler bar is mounted upon the vibrator.

14. A structure according to claim 12, in 20 which the means actuated by combined movement of the vibrator and arrest of movement of a feeler bar includes a pair of pivotally mounted wings adapted to be normally oscillated in unison by the feeler bars and to be 25 separately arrested in oscillation by arrest of movement of any feeler bar, and means engaging said wings and adapted to be moved by relative movement of the wings to impart movement to the means normally holding the 30 reciprocating member out of engagement with the knock-off element.

15. In a loom or the like including a normally stationary knock-off element, a normally reciprocating element for engagement 25 with said knock-off element to stop the loom, a shaft, and operative connection between said shaft and the reciprocating element, the combination of a warp stop motion including stationary notched guide bars, longitudinally 40 reciprocating notched feeler bars sliding on the guide bars and each adapted to be arrested in motion by engagement of a drop wire in a notch thereof and in a notch of the supporting guide bar, operative connection 45 between said shaft and said bars for reciprocation thereof, a pivoted arm, a link connected between said arm and the normally reciprocating member, a spring actuating said arm and link to hold the reciprocating member 50 out of engagement with the knock-off element, and operative connection between individual feeler bars and said pivoted arm for moving the arm upon arrest of movement of any feeler bar to release the reciprocating 55 member for engagement with the knock-off element.

16. In a loom or the like including a normally stationary knock-off element, a normally reciprocating element for engagement 60 with said knock-off element to stop the loom, a shaft, and operative connection between said shaft and the reciprocating element, the combination of a warp stop motion including stationary notched guide bars, longitudinally 65 reciprocating notched feeler bars sliding on

the guide bars and each adapted to be arrested in motion by engagement of a drop wire in a notch thereof and in a notch of the supporting guide bar, operative connection between said shaft and said bars for reciprocation thereof, 70 a pivoted arm, a link connected between said arm and the normally reciprocating member, a spring actuating said arm and link to hold the reciprocating member out of engagement with the knock-off element, and operative connection 75 between individual feeler bars and said pivoted arm comprising a pair of stop members normally moving in unison, means to arrest the movement of either of said stop members upon arrest of movement of any 80 feeler bar whereby relative movement of the stop members will result, and means actuated by the relative movement of the stop members to move said pivoted arm to release the reciprocating member for engagement with the 85 knock-off element.

17. In a loom or the like including a normally stationary knock-off element, a normally reciprocating element for engagement with said knock-off element to stop the loom, a shaft, and operative connection between said shaft and the reciprocating element, the combination of a warp stop motion including longitudinally reciprocating feeler bars, and operative connection between said bars and said reciprocating element normally holding the reciprocating element out of engagement with the knock-off element and operative upon arrest of movement of any feeler bar to permit engagement of the reciprocating element and knock-off element.

In witness whereof, I have hereunto set my hand.

WILLIAM H. BAKER.
